UNITED STATES PATENT OFFICE

NICK T. PUCKETT, OF INDIANAPOLIS, INDIANA, ASSIGNOR TO THE M. A. HOFFT COMPANY, OF INDIANAPOLIS, INDIANA, A CORPORATION OF INDIANA

FURNACE ARCH AND BLOCKS

Application filed December 12, 1927. Serial No. 239,303.

My invention relates to furnace arches and particularly to that type of furnace arch wherein there is provided a plurality of associated refractory blocks which form the 5 lining for the arch.

It is one of the objects of my invention to produce a mounting for the individual blocks of such character that the blocks may be readily inserted into a furnace arch in 10 such manner that if one of the blocks becomes defective it may be individually and readily removed and a substitute block placed in the arch without disturbing the other blocks and to provide such a mounting of a 15 character that the initial labor cost in installing the blocks, and in substituting one block for a broken one, may be reduced to a minimum.

For the purpose of disclosing my invention 20 I have illustrated one embodiment of the same in the accompanying drawings in which—

Fig. 1 is a partial longitudinal section of 25 a furnace provided with my improvement; Fig. 2 is a vertical section in the same plane as Fig. 1 on a larger scale of the block hanger and adjacent portions;

Fig. 3 is an end elevation of a portion of the suspension member, and

Fig. 4 is a perspective view of one of the 30 blocks.

In constructing the furnace arch I mount 35 therein a series of I beams 1 arranged preferably transversely of the furnace setting and equally spaced apart to coincide with the width of the refractory blocks to be used.

Each of the blocks 2 is provided with a 40 suspension member comprising a suspension rod 3 having at its lower end a head 4 adapted to enter a T slot 5 formed in the top of the block 2 and extending only part way into the block, preferably only far enough to permit the axis of the suspension member to be brought into alignment with the center of 45 gravity of the block. The upper end of the rod 3 is provided with a U shaped extension, each of the arms 6 thereof having at its upper end an opening to receive a pivot pin 7 of a locking dog 8, the arms of which are adapted 50 to straddle the arm 6. The rear ends of

these dogs are provided with weighted projections 9 extending at right angles to the dogs to maintain the dogs normally substantially in horizontal position and to lock the same against upward movement from 55 this position by engagement with the arms 6, 6. The upper ends of the arms 6 are provided with stop projections 10 which, engaging the weighted portions 9 when the dogs are tilted downwardly from the horizontal, 60 prevent the overthrow of the dogs.

In forming a refractory arch embodying 65 my improvements each block is provided with a suspension member which, after attachment to the block may, with the block, be projected upwardly. The dogs swing downwardly by their engagement with the bottom flange of the I beam and then drop into the 70 horizontal position, after moving past the flange, due to the weight of the portion 9. When the unit is slightly lowered the dogs come in contact with the flange to support their parts in position.

In event any one of the blocks becomes 75 damaged or broken the support may be very readily removed from position without disturbing the remaining blocks by breaking away entirely the damaged or broken blocks and then inserting the fingers up to maintain the dogs 8 in their depressed position as the suspension member is projected slightly upwardly. With the dogs in their depressed position the member may be lowered from 80 the I beam.

I claim as my invention:

1. A block suspension member for furnace arches comprising a stem having a head at its lower end and a pair of bifurcated arms at its upper end, dogs pivotally mounted on said arms and normally extending toward one another at an angle to said arms and means on said dogs adapted to engage the arms to prevent the yielding of said dogs in but one direction.

2. A support for furnace arch blocks comprising a stem having at its lower end a head and at its upper end a pair of bifurcated arms, supporting dogs pivotally mounted on said arms and normally extending toward one another at right angles to said arms and

weighted extension members on said dogs tending to move the same to their normal position and adapted to engage the arms to prevent the dogs from pivoting except in one direction.

5 3. A support for furnace arch block comprising a stem having at its lower end a head, and at its upper end a pair of bifurcated arms, supporting dogs pivotally 10 mounted on said arms, each comprising a bell crank, one arm of which normally extends toward the opposite dog and the other arm of which normally engages its bifurcated arm to prevent the dog from yielding in but one 15 direction.

10 In witness whereof, I, NICK T. PUCKETT, have hereunto set my hand at Indianapolis, Indiana, this 9th day of December, A. D. one thousand nine hundred and twenty-seven.

20 NICK T. PUCKETT.
